UNITED STATES PATENT OFFICE.

EBERHARDT PETER NICHOLSON, OF NEW YORK, N. Y., ASSIGNOR OF ONE-HALF TO JEREMIAH A. RICHARDSON, OF SOUTH NORWALK, CONNECTICUT.

FLUID-PRESSURE MOTOR.

No. 901,550.

Specification of Letters Patent.

Patented Oct. 20, 1908.

Application filed February 25, 1905. Serial No. 247,339.

To all whom it may concern:

Be it known that I, EBERHARDT PETER NICHOLSON, a citizen of the United States, residing in New York city, in the State of New York, have invented a new and useful Fluid-Pressure Motor, of which the following is a specification.

This invention relates to an electrically controlled fluid pressure motor especially adapted for use with heavy trucks, and it further relates to a motor having a double threaded shaft rotated continuously in one direction by the reciprocating motion of a piston sliding upon said shaft and engaging the said threads.

The object of the invention is to transform the reciprocating action of the piston into a continuous rotary movement of the shaft without dead centers, and further to provide means for electrically controlling the direction of rotation of the said shaft.

With these objects in view the invention consists in the novel features of construction and combination of parts hereinafter set forth, pointed out in the claims and shown in the accompanying drawings, in which:

Figure 1 is a longitudinal sectional view through the cylinder, the piston being partly in section and partly in elevation, and the shaft being in elevation. Fig. 2 is a section on the line 2—2 of Fig. 1. Fig. 3 is a section on the line 3—3 of Fig. 1. Fig. 4 is a detail sectional view of a housing carried by the cylinder, a lever and shaft being shown in elevation, and a switch bar in section. Fig. 5 is a section through one of the valves.

In these drawings A represents a cylinder provided with a housing A' adjacent its ends, and preferably on the upper side of the cylinder. A shaft B extends longitudinally through the cylinder and is rotatably journaled in the ends of the cylinder. The shaft B may be connected in any manner to the axle of the truck, or vehicle to be driven, as by sprocket wheels and chains, or by intermeshing gears, or if desired shaft B may itself be one of the axles of the vehicle. Within the cylinder the shaft B is enlarged as shown at B', and in the periphery of this enlarged portion is cut intersecting right and left hand threads B², thereby providing the portion B' of the shaft with a double spiral groove. A hollow cylindrical piston C closed at each end is adapted to travel back-

ward and forward upon the shaft B and at each end the piston is provided with suitable packing C' adapted to engage the grooves B² and prevent fluid from entering the piston, or from passing therethrough along the grooves of the shaft B.

The piston and cylinder are preferably elliptical in cross-section, as shown in Figs. 2 and 3 and the piston C is thereby prevented from rotating on the shaft B. This construction also provided room for the attachment carried within the piston. The devices consist of two flanged cylindrical rings D and D', the flange of the ring D being adapted to engage one set of threads on the shaft B and the flange of the ring D' being adapted to engage the other set. On each side of each ring is arranged a horse-shoe shaped electro-magnet E, two being on one side of the shaft and two upon the opposite side, and all supported in the piston by standards E'. The rings D and D' act as armatures for their respective magnets, and are attracted and held stationary by said magnets when the magnets are energized.

In the housing A' are journaled shafts A³ from which depend levers A², the free ends of which extend downwardly into the cylinder A and in the path of travel of parallel shoulders C² formed on the piston C midway its ends. The piston C has also flanges C³ at each end which snugly fit the sides of the cylinder A, and to prevent the said flanges from engaging the depending levers A² they are notched in alignment with said levers as shown at C⁴. To the outer ends of the shafts A³ are connected cranks F and the free ends of the cranks are connected by a switch bar F' carrying contact plates or points F². The cylinder A carries stationary contact plates or points, suitably insulated, said points F³ being engaged by the plates F² as the bar F' is shifted by contact of the shoulders C² with the levers A².

At opposite ends of the cylinder A I provide inlet pipes H and J and exhaust pipes H' and J', and in each is arranged a solenoidal valve K, of the usual construction of such valves.

Suitable electrical conductors extend from the contact plates F² and F³ to the said valves and also to the electro magnets E, the conductors for the electro magnets E being passed through one of the cylinder

heads in a cable G. The cable G comprises two sets of insulated conductors, one set extending to the electro magnets arranged opposite the ring D and the other set of conductors extending to the magnets E arranged opposite the ring D'. It will be understood that the electrical circuits and connections can be made in any desired manner.

In operation the piston C is driven by a fluid, steam, gas, air, or hydraulic pressure, admitted to the cylinder A through one of the inlet pipes.

Assuming the parts to be in the position shown in Fig. 1, the shoulder C² will have engaged the lever A² at the left hand end of the cylinder, as seen in the drawings, and the switch bar F' will have been shifted into the position shown in the said figure. The points F² being in proper contact the valves K will be opened at H and closed at H', and the exhaust valve at J' will be opened and the one at J closed. This movement of the bar will also cut out or deenergize the electro magnets E adjacent one of the rings, say the ring D, and will make the circuit leading to the magnets opposite the ring D'. The ring D' will therefore be held against rotation on the shaft by its magnets E. The pressure of fluid admitted through the inlet at H and the piston will be driven in a forward direction, and the ring D' being held against rotation and its flange engaging one of the threads on the shaft B the said shaft will be rotated. When the piston reaches the limit of its travel in a forward direction the other lever A² will be engaged by one of the shoulders C² and the circuits changed by the shifting of the bar F' so that the inlet at H' will be opened and also the exhaust at J, the others being closed. The piston C will therefore travel in the reverse direction, but as the ring D is now locked by the energizing of its magnets, and as it engages an opposite thread from that engaged by the flange of the ring D' the rotation of the shaft will be in the same direction, and the reciprocation of the piston C will therefore result in continuous rotation of the shaft.

Should the piston and shaft be stopped at the end of a forward movement of the piston, and the piston, after such momentary stoppage, is again started the rotation of the shaft will be reversed, and as long as the piston is kept in continuous reciprocatory motion the shaft will continue to rotate in the direction in which it was started.

In Fig. 5 I have shown a detail sectional view of one of the valves K', all of these valves being substantially of the same construction. In this figure, the pipe H', is shown as having an inwardly projecting shoulder H², provided with a concave face and from the opposite side of the pipe extends a branch H³, whereby a valve chamber

is formed. The solenoid comprises a core K², and a suitable winding K³.

A ball valve L is adapted to move vertically in the branch pipe and to seat in the concavity formed in the shoulder H², and when so seated the pipe H', is closed at this point as clearly shown in the said Fig. 5. The valve is provided with a stem L', which passes through the core K² and within the said core is provided with an armature L². The principle upon which the valve operates will be readily understood.

Having thus fully described my invention, what I claim as new and desire to secure by Letters Patent, is:—

1. A motor of the kind described comprising a cylinder, a rotatable shaft, arranged longitudinally in the cylinder, the said shaft having double spiral grooves formed in its periphery within the cylinder, a piston movable upon said shaft, flanged rings arranged within the piston adapted to engage the said grooves, electro magnets arranged in the piston and adapted when energized to hold the said rings against rotation with respect to the shaft, means for automatically energizing and deenergizing the said electro magnets alternately as the piston reaches its limit of travel, inlet and exhaust pipes at each end of the cylinder, solenoidal valves controlling said inlet and exhaust pipes, and means for automatically making and breaking an electric circuit connected with the said valves.

2. A device of the kind described comprising a cylinder having housings thereon, a rotatable shaft journaled in the cylinder, said shaft having right and left threads cut therein, a piston movable upon the shaft within the cylinder, a flanged ring within the piston, adapted to engage the right hand threads of the shaft, a similar ring within the piston adapted to engage the left hand threads of the shaft, an electro magnet arranged adjacent each of said rings, shoulders formed upon the piston, shafts journaled in the housings on the cylinder, levers carried by said shafts and having their free ends projecting in the path of the shoulders, cranks carried by the outer ends of the housing shafts, a switch bar connecting the said cranks, contact plates carried by the switch bar, stationary contact plates carried by the cylinder and adapted to be engaged by the contact plates carried by the switch bar, inlet and exhaust pipes arranged at each end of the cylinder, solenoidal valves arranged in each of said pipes, and electrical conductors extending from the contact plates to the said electro magnets and to the solenoidal valves as and for the purpose set forth.

EBERHARDT PETER NICHOLSON.
